DESIGN FOR A TABLE KNOCKER

Sebastian Cerrina, New York, N. Y.

Application February 25, 1938, Serial No. 75,412

Term of patent 7 years

To all whom it may concern:

Be it known that I, Sebastian Cerrina, a citizen of the United States and resident of the county of Queens, city and State of New York, have invented a new, original, and ornamental Design for a Table Knocker, of which the following is a specification, reference being had to the accompanying drawing, forming part thereof.

Fig. 1 is a perspective view of a table knocker, showing my new design.

Fig. 2 is a side view of the same.

The characteristic features of the design are the short reduced tapering conical upper end portion of the knocker head, the concave portion

joining the conical portion to the body of the knocker head and separated therefrom by a horizontal circular ridge at the juncture of the conical and concave portions, the flat front and rear vertical ornamental panels on the knocker head, the cylindrical handle extending from the knocker head at a point below its middle and at about the center of the rear panel and the surface ornamentation on the handle.

I claim:

The ornamental design for a table knocker, as shown and described.

SEBASTIAN CERRINA.
